UNITED STATES PATENT OFFICE

94,260

DESIGN FOR A SHOE

Alice Cohan, New York, N. Y., assignor to Bancroft Walker Co., Waltham, Mass., a corporation of Massachusetts

Application November 7, 1934, Serial No. 53,926

Term of patent 3½ years

To all whom it may concern:

Be it known that I, Alice Cohan, a citizen of the United States, residing at New York, in the county of New York and State of New York, have invented a new, original, and ornamental Design for a Shoe, of which the following is a specification, reference being had to the accompanying drawing, forming a part thereof, in which

Fig. 1 is a view in side elevation of a shoe showing my design; and

Fig. 2 is a plan view of the shoe.

I claim:

The ornamental design for a shoe, substantially as shown.

In testimony whereof, I have affixed my signature hereto.

ALICE COHAN.
